(57) **CLAIM**

The ornamental design for a computing device display screen with graphical user interface for generating a three-dimensional orofacial workflow, as shown and described.

DESCRIPTION

The sole FIGURE is a front view of the computing device display screen with graphical user interface for generating a three-dimensional orofacial workflow, showing the new design.

The evenly spaced broken lines showing an electronic device and portions of the graphical user interface, and the dot-dash lines showing the display screen, are included for the purpose of showing portions of the article which form no part of the claimed design.
